UNITED STATES PATENT OFFICE

LESTER E. SPRAY, OF WILKINSBURG, PENNSYLVANIA, ASSIGNOR TO THE UNION SWITCH & SIGNAL COMPANY, OF SWISSVALE, PENNSYLVANIA, A CORPORATION OF PENNSYLVANIA

RAILWAY SIGNALING APPARATUS

Application filed May 24, 1927. Serial No. 193,794.

My invention relates to railway signaling apparatus, and particularly to apparatus of the type involving signals having electric lamps.

5 One feature of my invention is the provision of means for causing a signal to give a more restrictive indication when the controlling apparatus for the signal is in condition to cause the signal to give a less restrictive indication and the lamp which should then be lighted is burned out.

I will describe several forms of apparatus embodying my invention, and will then point out the novel features thereof in claims.

15 In the accompanying drawings, Fig. 1 is a diagrammatic view showing one form of apparatus embodying my invention. Figs. 2, 3, 4, 5, and 6 are diagrammatic views showing modifications of the apparatus shown in 20 Fig. 1 and each embodying my invention.

Similar reference characters refer to similar parts in each of the several views.

Referring first to Fig. 1, the reference character S designates a railway signal, which, as 25 here shown, comprises a main group of lamps A and an auxiliary group of lamps C. Group A includes a proceed lamp G, a caution lamp Y, and stop lamp R. Group C includes a proceed lamp G¹ and usually other 30 lamps which form no part of the present invention.

The lamps in signal S are controlled by a main relay H and a distant relay D. The main relay H may be controlled in any 35 suitable manner, such, for example, as by a lever of an interlocking machine, or it may be a track relay connected with the track rails 1 and 1^a and so controlled automatically in accordance with traffic conditions. Relay

40 D is responsive to reversals of the relative polarity of the current supplied thereto, and may be controlled in any suitable manner by traffic conditions in advance of signal S. Signal S is also controlled in part by a distant 45 repeater relay D^R, the circuit for which is from terminal B of a suitable source of current, through contact 8 of relay D in either the normal or the reverse position, and the winding of relay D^R to terminal O of the 50 same source of current. It will be seen, there-

fore, that this relay is energized when relay D is energized in either direction, and is de-energized when relay D is de-energized. Preferably the relay D^R has slow-releasing characteristics.

The signal S is also controlled in part by a light-out relay E, the operation and function of which will appear hereinafter.

I will first assume that relay H is energized and that relay D is energized in the normal direction, that is, in such direction that its contact fingers are swung to the left. Proceed lamp G of group A is then lighted, the circuit being from terminal B, through the winding of relay E, front contact 6-6^a of relay H, contact 3-3^a of relay D and lamp G to terminal O. When relay H is energized, and relay D is energized in the reverse direction the caution lamp Y is lighted, the circuit being from terminal B through the winding of relay E, contact 6-6^a of relay H, contact 3-3^b of relay D and lamp Y to terminal O. The caution lamp Y is also lighted when relay H is energized and relays D and D^R are de-energized, the circuit then being from terminal B through the winding of relay E, contact 6-6^a of relay H, back contact 9 of relay D^R and lamp Y to terminal O. When relay H is de-energized, the stop lamp R is lighted by virtue of a circuit which passes from terminal B, through winding of relay E, back contact 6-6^b of relay H and lamp R to terminal O. Lamp G¹ of group C is provided with a circuit which passes from terminal B, through a contact 16, contact 14 of relay E, and lamp G¹ to terminal O. Contact 16 may be controlled by any suitable means, such, for example, as a lever of an interlocking machine.

I will now assume that while relay H is energized, and relay D is energized in the normal direction so that lamp G of group A should be lighted, this lamp burns out. Relay E will then be de-energized, and the stop lamp R will be lighted, the circuit being from terminal B, through back contact 12 of relay E, contact 11 of relay D in the normal position, front contact 17 of relay H and lamp R to terminal O. If lamp Y should be burned out when relay H is energized and relay D 100

- is energized in the reverse direction, stop lamp R will be lighted by virtue of the same circuit as before, except that this circuit will include contact 11 in the reverse position instead of in the normal position. If lamp Y should be burned out when relay H is energized and relays D and D^R are de-energized, lamp R will be lighted by virtue of a circuit which passes from terminal B, through back contact 12 of relay E, back contact 10 of relay D^R , contact 17 of relay H and lamp R to terminal O. I will now assume that relays H, D and D^R are all de-energized, so that stop lamp R should be lighted, that contact 16 is closed so that lamp G^I should be lighted, and that the stop lamp R is burned out. Relay E will then be de-energized, so that the circuit for lamp G^I is open at contact 14, with the result that lamp G^I cannot be lighted.
- If the direction of energization of relay D is reversed while relay H remains energized, it will be noted that relay E will momentarily be opened because both lamps G and Y will be momentarily extinguished. Lamp R will not be momentarily lighted, however, because the circuit for this lamp remains open at the back contact 10 of relay D^R , which, as stated hereinbefore, has slow-releasing characteristics.
- Referring now to Fig. 2, signal S in the form here shown comprises proceed, caution and stop lamps G, Y and R, which lamps are supplied with current by the secondaries of transformers T^G , T^Y and T^R , respectively.
- Signal S is controlled by a relay H, which, in the form here shown, is a three-position track relay having a winding constantly connected with the track rails 1 and 1^a. A repeating relay Q is controlled by relay H in such manner that relay Q is energized when relay H is energized in either direction, and is de-energized when relay H is de-energized.
- Assuming first that relay H is energized in the normal direction so that its contact fingers are swung to the left, the primary of transformer T^G is supplied with current by a circuit which passes from terminal B of a source of alternating current, through front contact 21-21^a of relay Q, winding of relay E, normal contact 18-18^a of relay H, and the primary of transformer T^G to terminal O of the same source of alternating current. Lamp G is therefore supplied with current and is lighted. When relay H is energized in the reverse direction, the caution lamp Y is lighted by virtue of a circuit which passes from terminal B, through contact 21-21^a of relay Q, winding of relay E, contact 18-18^b of relay H and the primary of transformer T^Y to terminal O. When relays H and Q are de-energized, the stop lamp R is lighted, the circuit being from terminal B through back contact 21-21^b of relay Q, and the primary of transformer T^R to terminal O. I will now assume that while relay H is energized in

the normal direction the proceed lamp G is burned out. The caution lamp Y will then be lighted, the circuit being from terminal B, through front contact 21-21^a of relay Q, back contact 12 of relay E, normal contact 19-19^a of relay H and the primary of transformer T^Y to terminal O. I will next assume that while relay H is energized in the reverse direction the caution lamp Y is burned out.

Stop lamp R will then be lighted, the circuit being from terminal B, through contact 21-21^a of relay Q, back contact 12 of relay E, reverse contact 19-19^b of relay H, front contact 22 of relay Q and the primary of transformer T^R to terminal O.

Referring now to Fig. 3, the apparatus shown in this view is similar to that shown in Fig. 2, except as to the detailed arrangement of the circuits. Assuming first that relay H is energized in the normal direction, the proceed lamp G is lighted, the circuit being from terminal B through winding of relay E, normal contact 18-18^a of relay H and the primary of transformer T^G to terminal O. Relay Q is then energized by virtue of a circuit which includes the normal contact 20-20^a of relay H. When relay H is energized in the reverse direction, the caution lamp Y is lighted, the circuit being from terminal B, through winding of relay E, reverse contact 18-18^b of relay H and the primary of transformer T^Y to terminal O. Relay Q is then energized by virtue of a circuit which passes from terminal B, through reverse contact 20-20^b of relay H, contact 22 of relay E and the winding of relay Q to terminal O.

When relay H is de-energized, relay Q is also de-energized, and the stop lamp R is then lighted by virtue of a circuit which passes from terminal B, through back contact 21 of relay Q and the primary of transformer T^R to terminal O.

I will now assume that while relay H is energized in the normal direction the proceed lamp G is burned out. Relay E will then be de-energized, and caution lamp Y will be lighted by virtue of a circuit which passes from terminal B, through back contact 12 of relay E, normal contact 19-19^a of relay H and the primary of transformer T^Y to terminal O. Relay Q will at such time be energized, so that the stop lamp R is not lighted. I will now assume that while relay H is energized in the reverse direction the caution lamp Y is burned out. Relay E will then be de-energized, with the result that relay Q will also be de-energized, and stop lamp R will then be lighted by virtue of the same circuit as that traced hereinbefore for this lamp.

As here shown, relay Q is also provided with contacts 37 and 38 which constitute a pole-changer included in the track circuit for the section in the rear of signal S, whereby the relay H for such section in the rear

can be energized in the normal direction when and only when relay Q is energized. The result of this is that whenever stop lamp R of signal S is lighted for any cause, 5 whether in normal operation or because of failure of lamp Y, the proceed lamp for the signal in the rear cannot be lighted.

Referring now to Fig. 4, the signal S comprises a proceed lamp G, a main caution lamp Y, an auxiliary caution lamp Y¹ and a stop lamp R. The signal is controlled by a three-position track relay H and a repeater relay Q, but the light-out relay E is omitted. Relay Q is controlled by contact 19 of relay H in such manner that relay Q is energized when relay H is energized in either the normal or the reverse direction, but is de-energized when relay H is de-energized. First assuming that relay H is energized in the 15 normal direction, the proceed lamp G is lighted by virtue of a circuit which passes from terminal B, through front contact 21-21^a of relay Q, normal contact 18-18^a of relay H and the primary of transformer T^g to terminal O. When relay H is energized in the reverse direction, the primary of transformer T^y is supplied with current by a circuit which passes from terminal B, through front contact 21-21^a of relay Q, reverse contact 18-18^b of relay H and the primary of transformer T^y to terminal O. The main caution lamp Y is then lighted by a circuit which passes from the left-hand terminal of the secondary 32 of transformer 25 T^y, through an impedance 23 and lamp Y to the right-hand terminal of the secondary 32. The value of impedance 23 is substantially the same as the impedance of lamp Y. One terminal of lamp Y¹ is connected with 30 the middle point of secondary 32, and the other terminal of lamp Y¹ is connected in the circuit for lamp Y between the impedance 23 and the lamp Y. The two terminals of lamp Y¹ are therefore at the same potential 35 and so this lamp is extinguished. If, however, lamp Y should burn out while transformer T^y is energized, the terminals of lamp Y¹ will be at different potentials and so this lamp will be lighted. When relay 40 H is de-energized, relay Q is likewise de-energized and the stop lamp R is then lighted by virtue of a circuit which includes back contact 21-21^b of relay Q and the primary of transformer T^r.

Referring now to Fig. 5, relays H and Q are controlled as in Fig. 4. When relay Q is energized, primary 24 of a transformer U is supplied with alternating current through front contact 21-21^a of relay Q. When relay H is energized in the normal direction, the proceed lamp G is energized by a circuit which passes from the right-hand terminal of secondary 25 of transformer U, through an impedance 27, primary of transformer 55 T^g, normal contact 19-19^a of relay H to

the left-hand terminal of secondary 26, and from the right-hand terminal of secondary 26, through normal contact 18 of relay H to the left-hand terminal of secondary 25. One terminal of the primary of transformer T^y is connected in this circuit at a point between impedance 27 and transformer T^g, whereas the other terminal of the primary of T^y is connected with the right-hand terminal of secondary 26 and with the left-hand terminal of secondary 25. The value of impedance 27 is the same as the impedance of the primary of transformer T^g when lamp G is lighted. When lamp G is lighted, then, the two points with which the primary of transformer T^y is connected are at the same potential, so that lamp Y is extinguished. If lamp G burns out, however, while relay H is in the normal position, lamp Y is then supplied with current and so the signal indicates caution. When relay H is energized in the reverse direction, the circuit for transformer T^g is opened at contact 19-19^a, and the circuit for transformer T^y is closed at contact 19-19^b. The stop lamp R is controlled in the usual manner through back contact 21-21^b of relay Q.

Referring now to Fig. 6, the two lamps G and Y are supplied with current by two secondaries 29 and 30 of a transformer T, the primary 28 of which is supplied with alternating current when relay Q is energized. When relay H is energized in the normal direction, the circuit for lamp G is from the left-hand terminal of secondary 20 through impedance 31, lamp G, normal contact 18-18^a, and secondary 29 to the right-hand terminal of secondary 30. One terminal of lamp Y is connected in this circuit at a point between impedance 31 and lamp G, whereas the other terminal of lamp Y is connected in this circuit at a point between secondaries 29 and 30. The value of impedance 31 is substantially the same as that of the lamp G, so that when lamp G is lighted the two terminals of lamp Y are at the same potential and this lamp is extinguished. If lamp G burns out, however, the two terminals of lamp Y are at different potentials, and so this lamp becomes lighted. When relay H is energized in the reverse direction, secondary 29 is disconnected from lamp G and lamp Y is then supplied with current from secondary 30, through impedance 31. When relay H is de-energized, relay Q is also de-energized and lamp R is then supplied with current through back contact 21-21^b of relay Q.

Although I have herein shown and described only a few forms of apparatus embodying my invention, it is understood that various changes and modifications may be made therein within the scope of the appended claims without departing from the spirit and scope of my invention.

Having thus described my invention, what

I claim is:

1. In combination, a railway signal having proceed, caution and stop lamps, controlling means for selectively lighting said lamps, means for lighting said caution lamp when said controlling means is in condition for lighting the proceed lamp if the proceed lamp is burned out, and means for lighting said stop lamp when said controlling means is in condition for lighting said caution lamp if the caution lamp is burned out.
2. In a railway signaling system, a signal relay capable of energization in normal and reverse directions, a light signal comprising a proceed lamp and a caution lamp, a proceed lamp circuit controlled by a normal contact of said signal relay, a normal circuit for said caution lamp controlled by a reverse contact of said signal relay, and means controlled by said proceed lamp circuit for causing said caution lamp to be lighted when said signal relay is energized for lighting said proceed lamp but said proceed lamp is burned out.
3. In a railway signaling system, a home relay capable of energization in normal and reverse directions, a home repeater relay, a signal having proceed, caution and stop lamps, a light-out relay, a proceed lamp circuit including said light-out relay and a normal contact of said home relay, a normal circuit for said caution lamp including said light-out relay and a reverse contact of said home relay, an auxiliary circuit for said caution lamp including a back contact of said light-out relay and a normal contact of said home relay, a circuit for said stop lamp including a back contact of said home repeater relay, a first circuit for said home repeater relay including a normal contact of said home relay, a second circuit for said home repeater relay including a reverse contact of said home relay and a front contact of said light-out relay, and pole-changing contacts of said home repeater relay for controlling the polarity of control current for signaling apparatus in the rear of said signal.
4. In a railway signaling system, a home relay capable of energization in normal and reverse directions, a signal having proceed, caution and stop lamps, a light-out relay, a proceed lamp circuit including said light-out relay and a normal contact of said home relay, a main caution lamp circuit including said light-out relay and a reverse contact of said home relay, an auxiliary caution lamp circuit including a back contact of said light-out relay and a normal contact of said home relay, and means for lighting said stop lamp when either said home relay or said light-out relay is de-energized.
5. In combination, a railway signal having a main lamp and a second lamp, controlling means for selectively lighting said lamps, means for lighting said second lamp

when said controlling means is in condition for lighting said first lamp but said first lamp is burned out, and means for controlling the operation of signaling apparatus in the rear of said signal to one position or another according as said main lamp is burned out or not.

In testimony whereof I affix my signature.
LESTER E. SPRAY.
